GOLF PUTTER

Robert H. Phinny, R.R. 2, Fremont, Mich. 49412

Continuation-in-part of abandoned design application Ser. No. 200,668, Dec. 7, 1971. This application Apr. 6, 1972, Ser. No. 241,868

Term of patent 14 years

Int. Cl. D21—02

U.S. Cl. D34—5 GC

FIG. 7

FIG. 8

FIG. 9

FIG. 10

FIG. 11

FIG. 1 is a perspective view of the putter;
 FIG. 2 is a side elevation view of the putter;
 FIG. 3 is a plan view of the putter head;
 FIG. 4 is a front elevation view of the putter head;
 FIG. 5 is a rear elevation view of the putter head;
 FIG. 6 is a sectional view of the putter head taken along section line VI—VI of FIG. 3;
 FIG. 7 is a perspective view of an alternative embodiment of the putter;
 FIG. 8 is a plan view of the alternative embodiment;
 FIG. 9 is a rear elevation view of the alternative embodiment;
 FIG. 10 is a plan view of another embodiment of the putter; and
 FIG. 11 is a perspective view of the embodiment shown in FIG. 10.
 This is a continuation-in-part of Ser. No. D. 200,668, filed Dec. 7, 1971, now abandoned.

I claim:

The ornamental design for a golf putter, substantially as shown and described.
